GAS-FUELED IGNITER SYSTEM

Harry E. Lake, Bethel, Conn., assignor to Preferred Utilities Manufacturing Corporation, New York, N.Y., a corporation of Delaware

Application November 1, 1954, Serial No. 465,830

2 Claims. (Cl. 158—115)

This invention relates to a new and improved igniter system which eliminates the need for fuel jets and includes a self-compensating feature which insures correct gas-air ratios for the igniter despite variations in fuel supply pressure, draft, rate of fuel consumption, humidity, and other factors.

Since the advent of natural gas into territories where automatic oil burner systems are in use, considerable difficulty has been experienced in the use of gas-electric igniters which previously worked satisfactorily on producer gas.

Natural gas, being principally methane, has a very small range of gas-air mixtures at which flame propagation takes place at the necessary speed. Because of this small gas-air range, the air and gas jet adjustments become extremely critical under the varying conditions of gas pressure, draft, rate of fuel consumption with its controlled primary and secondary air mixture, humidity, and the introduction of air from the burner fan case. In some sections the natural gas and the producer gas are mixed creating further problems.

Attempts to meet this situation by the provision of different size gas jets has not been entirely satisfactory. It will be appreciated that gas jet type igniters using natural gas will not function properly should the gas supply line pressure vary to any great extent and should a break in the line or a large drain thereon develop reducing the supply pressure below the minimum operating pressure for the igniter, the igniter will fail completely. Even under normal conditions, the small gas-air range of natural gas causes many difficulties in using gas jets due to the extremely delicate adjustments which must be made and maintained. The cost of maintaining such igniters in operating condition is not inconsequential.

By my invention the problem of manufacture, installation and maintenance of precisely sized gas jets is eliminated. My invention comprises an igniter system which has a compensating venturi means within a housing; means are provided for supplying a flow of air through the venturi; and means are provided for continuously maintaining a source of fuel at the venturi which is at a predetermined steady pressure, zero gauge pressure, to enable the formation of a combustible mixture having a substantially constant fuel-air ratio for all rates of flow. A suitable pressure reducing valve in the gas supply line establishes the source of zero gauge pressure fuel which will be available over an extremely large range of supply line pressures. My igniter system, therefore, will operate satisfactorily below the minimum pressure level at which gas jet igniters fail. Also in combination in my igniter system is an electric spark means which has an igniter from which is emitted a cone-like spray of sparks.

To protect the igniter from becoming short-circuited by the formation of carbon filaments and to provide an added venturi effect, a tube is provided around the electric spark means which has a by-pass hole commu-

2

nicating with the air supply. In this manner a protective flowing layer of air is formed within the tube and directed past the igniter through the cone-like spray of sparks. Fouling and filament formation are thereby prevented. Further the blanketing stream of air so formed provides an added venturi effect on the fuel supply capable of forming a mixture having a substantially constant fuel-air ratio for all rates of flow.

The gas port to the housing is of sufficient size to supply the required amount of gaseous fuel to the venturi means without appreciable friction loss. In the average size igniter, the gas port may have a minimum size of one-quarter inch diameter for it has been discovered that this size port is suitable for burning gas with any heat content from 500 to 2500 B. T. U.'s per cubic foot. It will be appreciated that larger igniters of the type, for example, capable of burning more than 50 cubic feet per hour of natural gas would require a larger port to insure negligible friction losses. Therefore the size of the gas port must be large enough to supply the capacity of the igniter at zero gauge pressure, otherwise the inspiring effect of the air would be reduced by creating a vacuum on the gas line.

Other and further advantages and objects of my invention will become more apparent hereinafter as the same becomes better understood from an examination of the specification and claims in conjunction with the accompanying drawings wherein:

Fig. 1 is a fragmentary side view partly in section showing a horizontal rotary burner equipped with an igniter and a pressure reducer for the igniter gas supply;

Fig. 2 is a graph showing the speed of uniform movement of flames of methane and producer gas in air;

Fig. 3 is a front end fragmentary view of a horizontal rotary burner, flame rod and the igniter of my invention; and

Fig. 4 is a rear end view of the igniter showing the air inlet, the gas inlet, and the electric spark means.

Referring now to Fig. 1, it will be seen that the igniter 14 is suitably mounted adjacent a horizontal rotary oil burner 15 of conventional design, this type burner being shown for purposes of illustration only. The burner 15 is supplied with primary air by a suitable blower (not shown), the air for the igniter 14 being directed at the air inlet 16 from the fan case 17 by means of a nozzle 18. If desired, a direct pipe connection can be made, but experimentation has shown this added part to be unnecessary. Where an induced draft fan is used, the negative pressure in the furnace may be sufficient to draw the required air through the igniter 14, thereby eliminating the necessity for a blower supply.

The igniter 14 is attached to a nozzle shield 19 by means of ears 20 (Fig. 4) which extend from the main body 22 of the housing indicated generally by numeral 21. The housing is made up of the main body 22 having a venturi means and a flame barrel 24 having a flame retention ring 25. The main body has a circular opening 26 at its forward end which surrounds a concentrically disposed disc igniter 27, the disc igniter being attached to the forward free end of an electric spark means 28. The rear end portion of the electric spark means is rigidly mounted in the rear end portion of the main body 22 by suitable means, such as the threaded clamping collar 29 shown in Fig. 1. This collar forces the spark plug toward the annular shoulder 30 in the main body 22 and clamps the spark plug 28 as well as a protective air tube 31 in proper rigid position within the main body. The forward body portion of the spark plug is of less diameter than the rearward portion to provide an annular air conduit 32 with the forward portion of the protective air tube 31. The rearward portion of the air tube 31 con-

tacts and is supported by the rearward portion of the spark plug 28.

The main body 22 has a venturi means which surrounds the protective air tube 31 and is arranged to direct a cylinder of air and fuel past the peripheral sparking edge of the disc igniter 27, an inner protective cylindrical layer of air alone being supplied also to prevent short circuiting of the disc electrode as will be explained. The venturi means includes an inwardly extending partition member 33 which surrounds and is outwardly spaced from the protective air tube 31 and which defines a rearward air chamber 34 and a forward gas chamber 35.

A gas line 36 connects the gas port or opening 37 of the gas chamber to a pressure reducing valve 38 which is in turn connected to the main gas supply line 39. The pressure reducing valve reduces the gas pressure down to approximately zero gauge pressure so there is no gas flow except as demanded by the suction produced by air flow. For small igniters, a simple pressure reducing valve of well known design is very satisfactory. For purposes of illustration, however, a well known governor type pressure reducing valve is shown. In this valve the gas in supply line 39 tends to push the valve disc 40 open, but this tendency is exactly balanced by the upward push against the lower diaphragm 41. The weight of all moving parts is always exactly balanced by the sensitive spring 42. So long as the pressure in the diaphragm case under the upper diaphragm 43 is the same as that above the diaphragm, the valve will not move, but if this pressure drops because gas is drawn away through gas line 36 to gas chamber 35, the difference in pressure on the two sides of the upper diaphragm 43 at once moves the valve disc 40 down, allowing more gas to go through to restore the balance. Regardless how much gas is being drawn, the valve opening is just enough to supply that much gas at exactly zero gauge or atmospheric pressure or whatever pressure is imposed on top of the upper diaphragm 43. As the top diaphragm through port 44 is normally open to the atmosphere, the gas delivery pressure is also atmospheric. Any pressure may be selected as a base pressure by connecting port 44 to a source of the desired pressure.

The partition member 33 and the forward end wall 45 of the main body 22 provide forwardly and inwardly sloping walls directed toward the disc igniter 27 for the air chamber 34 and the gas chamber 35, respectively. The protective air tube 31 has an annular series of bypass holes 46 adjacent the air chamber 34 which bypass air around the venturi and through the annular air conduit 32 between the protective air tube 31 and the spark plug 28 to form a protective annular cylinder of air which alone contacts the peripheral sparking edge of the disc igniter 27, thereby preventing the formation of a carbon filament from the disc igniter to the main body. Should such a filament form, sparking would cease since the current would pass along the filament. The protective air tube prevents this as well as any excessive buildup of foreign matter on the peripheral edge. The annular air conduit 32 produces a venturi effect on the gas chamber 35 and aids in the production of a final fuel-air mixture having a substantially constant ratio for all rates of air flow. The tube 31 and the annular air conduit 32 therefore provide an inner venturi means and the main body 22 including its partition 33 forms in part the outer venturi means.

The inner edge of the partition member 33 is spaced outwardly from the protective air tube 31 to form a constricted annular air passage 47 for the flow of high velocity air. This air draws gas from the gas chamber 35 in direct proportion to the air flow and the resultant gas-air mixture then flows as an annular cylinder between the wall of the circular opening 26 and the inner annular protective cylinder of air.

Sparks from the disc igniter 27 form an annular spray

of outwardly and forwardly moving sparks to the outwardly flared forward end 48 of the main body.

The flame barrel 24 surrounds and is connected by a screw 49 to the reduced forward end of the main body. The flame retention ring 25 is positioned within the forward end of the flame barrel, the holes therein causing a portion of the fuel-air mixture to burn as a plurality of small flames which insure continued burning of the main center flame of the igniter at all firing rates.

As seen in Figs. 1 and 4, the air inlet 16 is an internally threaded opening to the air chamber 34. The one adjustment needed for this igniter, namely the control of the volume range of air used by the igniter, may be easily made by the addition of a diameter reducing externally threaded tube to the air inlet.

The air inlet is on one side of the main body 22 and the gas inlet 37 (which includes a weatherhead fitting) is on the other. It will be noted that the gas inlet 37 comprises a conduit which extends forwardly through the main body 22 to the opening (Fig. 1) in the gas chamber. Through experimentation and tests it has been discovered that the minimum diameter of the gas port to the gas chamber is preferably of the order of one-quarter inch for average size igniters. By making the gas port of sufficient size to supply the required amount of gaseous fuel to the venturi means without appreciable friction loss, it is possible to obtain the efficient and satisfactory burning of methane, which as seen in Fig. 2 has a small gas in air percentage range suitable for flame movement, as well as producer gas which, as seen in Fig. 2, has a larger gas in air percentage range.

The igniter is positioned just above the atomizer of the horizontal rotary oil burner so that its flame will light the oil from the main burner as soon as it leaves the atomizer. It will be apparent that this igniter may be used on gas burners and other types of oil burners by suitable modifications of design and mounting.

A suitable flame rod 50 of well known design is mounted adjacent the igniter as shown in Fig. 3; its function is to prove that there is a pilot burning before the oil valve on the oil burner can open.

While a specific structure has been shown and described for illustrative purposes, it will be understood that the invention is not so limited and for that reason I wish to limit myself only within the scope of the appended claims.

I claim:

1. A gas igniter system for burners wherein said burners have a primary air source at a pressure higher than the pressure in the furnace which is sufficient to meet the requirements of all firing rates, said igniter system comprising a hollow main body having an opening at its forward end, an electric spark means mounted at the rear end portion of said main body and extending centrally therethrough and having an igniter disc mounted at its free end concentric with said opening, a tube surrounding and outwardly spaced from said spark means and having a forward free end terminating rearwardly of said igniter disc, said tube having an air bypass hole and forming an annular conduit with the electric spark means, said tube extending approximately to the periphery of said igniter disc, said main body having a venturi means in fluid communication with said opening at said forward end including a partition extending inwardly from the wall of said main body and defining with said wall a rearward air chamber and a forward gas chamber, the inner edge of said partition surrounding and being outwardly spaced from said tube at a point forwardly of said bypass hole whereby one portion of air flow is directed through said bypass hole and the remaining portion of air flow is directed through said venturi means, said main body having an air inlet opening adapted for conducting air from said primary air source to said air chamber, said main body having a gaseous fuel inlet port of sufficient size to supply the required amount of gaseous fuel to said

gas chamber without appreciable friction loss, and means for providing a source for gaseous fuel at a constant pressure of substantially zero gauge pressure, said venturi means being adapted to cause air flow from said rearward air chamber to said opening at said forward end to draw gaseous fuel from said forward gas chamber in amounts varying substantially directly with the varying air flow from said primary source.

2. A gas igniter for burner systems wherein said burners have a primary air source at a pressure higher than the pressure in the furnace which is sufficient to meet the requirements of all firing rates, said igniter comprising a hollow main body having an opening at its forward end, an electric spark means mounted at the rear end portion of said main body and extending centrally therethrough and having an igniter disc mounted at its free end concentric with said opening, a tube surrounding and outwardly spaced from said spark means and having a forward free end terminating rearwardly of said igniter disc, said tube having an air bypass hole and forming an annular conduit with the electric spark means, said tube extending approximately to the periphery of said igniter disc, said main body having a venturi means in fluid communication with said opening at said forward end

5 including a partition extending inwardly from the wall of said main body and defining with said wall a rearward air chamber and a forward gas chamber, the inner edge of said partition surrounding and being outwardly spaced from said tube at a point forwardly of said bypass hole whereby one portion of air flow is directed through said bypass hole and the remaining portion of air flow is directed through said venturi means, an air inlet opening in said main body communicating with said rearward air chamber, and a gas inlet opening in said main body communicating with said forward gas chamber.
